UNITED STATES PATENT OFFICE.

BRUNSON SIMPSON McCUTCHEON AND HAROLD EDWARD WILLIAMS, OF WASHINGTON,
DISTRICT OF COLUMBIA.

APPARATUS FOR REPRODUCING ROTARY MOTION.

1,322,319.

Specification of Letters Patent.

Patented Nov. 18, 1919.

Application filed November 8, 1918. Serial No. 260,370.

To all whom it may concern:

Be it known that we, BRUNSON SIMPSON McCUTCHEON and HAROLD EDWARD WILLIAMS, citizens of the United States, residing 5 at Washington, in the District of Columbia, have invented certain new and useful Improvements in Apparatus for Reproducing Rotary Motion, of which the following is a specification.

10 Our invention relates to electrical apparatus for causing rotary motion of a body or member, to be reproduced in a remote member or body.

15 The invention comprises broadly two rotary members—a transmitter and a receiver—remote one from the other, and electro-mechanical connections between the two members whereby rotary movement of the transmitter is communicated to the receiver 20 by means of electrical impulses.

The object of our invention is to provide a simple and inexpensive apparatus capable of accurately indicating or reproducing in a member clockwise or counter-clockwise rotary motion of a distant member.

In the accompanying drawings:

Figure 1 is a plan view of the transmitter showing the parts in normal position or at rest;

30 Figs. 2, 3 and 4 are fragmentary detail views showing the transmitter in different positions;

Fig. 5 is a plan view of the receiver;

Fig. 6 is an edge view of Fig. 5 with the 35 solenoids removed;

Figs. 7, 8 and 9 are fragmentary detail views of the receiver in different positions; and

Fig. 10 is a schematic view of the transmitter and receiver and electrical connections therebetween.

Referring more specifically to the drawings in which like reference numerals indicate corresponding parts throughout the several views, 1 denotes what may be termed the transmitter and 2 the receiver.

The transmitter comprises a pair of spaced ratchet wheels or toothed disks 3 and 4 fixedly mounted upon a shaft 5 in turn 50 rotatably supported in a base plate or other suitable support 6. These disks are similar in size and shape with the exception that their respective peripheral teeth 7 and 8 are oppositely disposed or cut. The distance between the teeth of each disk or in

other words the angle subtended by any one of the teeth will represent the least angle or rotary movement which it is desired to transmit.

9 represents a rocking guide plate pivoted to the base plate 6 at 11 through which slides a pawl 13. The pawl 13 which is slightly offset at its free end is normally held in engagement with the teeth of the disk 3 by springs 15 and 16 in an obvious manner. 60 Sliding movement on the return stroke of the pawl 13 through the guide openings 19 in the plate 9 is limited by the stop pin 21 coming in contact with the flange 23.

As the shaft 5 is rotated in a clockwise 65 direction, either by hand crank or by other means the pawl 13 is pulled through the guide plate 9 against the tension of coil spring 16, the action of spring 15 insuring close contact between the pawl and ratchet 70 wheel during this movement.

When the ratchet wheel has been rotated a distance equal to that of the space between two teeth the pawl 13 slips off the segmental shaped periphery of the particular tooth 7 engaged thereby and is drawn back to Fig. 1 position where it is picked up by the next or adjacent advancing tooth. It will be understood that during the advance movement of the pawl 13 the cam projection 27 does not engage the roller 25. 75

During the latter or return movement of the pawl 13 the roller 25 mounted on one end of a rocking arm 26 is engaged by the cam projection 27 formed on the pawl thus 80 accomplishing a purpose about to be described.

The arm 26 is pivoted intermediate its ends as at 28 to the base plate 6 and carries at the end opposite to the roller 25 a contact spring 29. A coil spring 30 secured to the 95 base plate 6 at one end and to the arm 26 at its other end normally maintains the arm against the stop 31 and maintains the point 32 of the contact spring out of engagement with the point 33 of the electrical contact 100 member or pole piece 34.

When the cam projection 27 engages the roller 25 the arm 26 is rocked on its pivot 28 against the tension of spring 30 causing the points 32 and 33 to contact. As the 105 pawl 13 is drawn back to its original or Fig. 1 position by spring 16 the cam 27 moves out of contact with the roller 25 permitting the spring 30 to oscillate the arm 26 and break contact between the points 32 110

and 33, thus completing the clockwise cycle of operation of the transmitter. The period of duration of this contact being controlled solely by the action of spring 16 and by the 5 contour of the teeth 7 and shape of the cam 27 is entirely independent of the speed with which the disk 3 is rotated. It may also be noted here that electric contact is not effected until the transmitter has been moved 10 to the point when the pawl has been entirely disengaged from the tooth which has been advancing it.

The mechanism just described will transmit clockwise motion only to the receiver in 15 a manner hereinafter explained.

In order to rotate the receiver in a reverse or counter-clockwise direction and thereby reproduce corresponding counter-clockwise movement of the transmitter, a duplicate set 20 of transmitter parts is provided on the opposite side of the transmitter disks, identical with those previously described. While the cycle of operation of this set of transmitter parts is identical with the cycle described 25 and it is believed will be readily understood from the foregoing the following brief explanation thereof is given.

When the transmitter disks are rotated in a counter-clockwise direction the pawl 13' is 30 carried outwardly or forwardly through the guide plate 9', by the teeth of disk 4. Continued rotation of the disk 4 causes the pawl to ride off the tooth with which it engages whereupon the spring 16' returns the pawl 35 to its original position or Fig. 1 position. During this return movement the cam projection 27' engages the roller 25' carried by the arm 26', rocking the latter on its pivot 28' and causing the contact points 32' and 40 33' on the pole piece 34' and the spring 29' respectively to make contact. A spring 30' normally maintains the arm 26' against the stop screw 31' in the position illustrated in Fig. 1 while the spring 15' rocks the guide 45 plate 9' on its pivot 11' and holds the pawl 13' in engagement with the disk 4. The stop 21' on the pawl engages the flange 23' of the plate 9' and serves to limit the withdrawal of the pawl through said plate.

50 The cycle of operation just described causes the receiver to rotate in a counter-clockwise direction a distance corresponding to that of the movement of the transmitter disks as will be presently described.

55 In practice we have found that the pawls 13 and 13' are apt to wear, due to constant engagement with the teeth of the disks or ratchets 3, and 4 and when this occurs one of the pawls, for example pawl 13, is apt to 60 become disengaged before the disk or ratchet 4 has been advanced to the proper position to be engaged by the pawl 13'. Premature disengagement of the pawl, obviously results in lost motion and consequently movement 65 of the transmitter will not be accurately re-

produced by the receiver. This action is also liable to occur should there be any slight inaccuracy in shape or size of the parts mentioned. We overcome this difficulty by providing a lever 18 pivoted to the base plate 6 70 at 14. Should the pawl 13 slip off the tooth of the disk or ratchet 3 prematurely, the pin 12 on the end of the pawl 13 would engage and rock the lever 18 on its pivot. The other end of the lever 18 then comes in contact with a pin 12' carried by the pawl 13' slightly advancing the latter as seen in Fig. 1.

The receiver 2 comprises a pair of spaced ratchet wheels 35 and 36 fixed to a shaft 37 80 having its bearing in a base plate 38 or other suitable support. The ratchet teeth 39 and 40 are oppositely disposed, as is true of the transmitter. A lever arm 41 rotatably mounted on the inner end of the shaft 37 85 adjacent the ratchet wheel 36 carries at its free end a pawl 42. This pawl which is in the form of a bell-crank lever is pivoted to the arm 41 at 43, one arm 44 of the pawl being adapted to engage one of the teeth 40 90 of the ratchet wheel 36 while the other arm 45 thereof oscillates between two stops 46 and 47 on the end of the arm 41.

When contact is made between the points 32-33 during the clockwise rotation of the transmitter disks, the circuit of relay 63 is completed by the following path: battery 65, conductor 68, contact 33, contact 32, conductor 67, winding of relay 63 and conductor 69 to the opposite side of battery 65. The operation of the relay 63 in attracting its armature 64 in turn completes by the following path, the circuit of the solenoid 49, the core 50 of which is connected to one end of a rod or the like 52 in turn connected to the arm 45 of the pawl 42 as at 51: battery 62, armature 64, contact of relay 63, conductor 48 winding 79 of solenoid 49, conductor 61 to the opposite side of battery 62. (It will be understood that an electric magnet could be readily used in lieu of a solenoid). The winding of the solenoid, thus becomes energized and the core 50 will be drawn into the solenoid thus rocking pawl 42 on its pivot 43 until the arm 45 rests against stop 47. Further movement of the core will cause the lever arm 41 to rotate clockwise about the shaft 37 or axis of the receiver, thus bringing the arm 44 of the pawl into engagement with one of the teeth of the ratchet wheel 36 115 and causing the latter to also rotate in a clockwise direction.

The condensers 66 and 66' are for the purpose of reducing the spark caused when contacts 32, 33, 32' and 33' disengage.

When contact is broken between the points 32-33 of the transmitter a coil spring 53 first moves the arm 45 of the pawl 42 against the stop 46 and then returns the lever arm 41 and the solenoid core 50 to the Fig. 5 posi-

tion. If another electrical impulse is now sent over the circuit to the solenoid 49 due to the continued clockwise rotation of the transmitter, the receiver is again rotated in 5 the same direction in the manner previously described.

The degree of clockwise rotation of the ratchet wheel 36 is limited to one tooth by an escapement lever 54 pivoted to the base 10 plate at 55. A compression spring 56 maintains the offset hooked end 57 of this lever against the stop 58 and in engagement with or in the path of rotation of the teeth of the ratchet wheel 35 before the finger 59 on the 15 pawl 42 has traversed the cam shaped protuberance or contour 60 of the escapement lever. During the period of time which the finger 59 engages the cam portion 60 and while the lever arm 41 is at rest, the end 57 20 of the escapement lever is moved out of engagement with the ratchet teeth 39. The escapement lever 54 is held out of engagement with the teeth 39 of the disk 35 during the time the finger 59 traverses the cam 25 protuberance 60 of the escapement lever 54. This permits the disks 35 and 36 to be rotated. The end 57' of the escapement lever 54' does not limit the rotation of the disks 35 and 36 in a clockwise direction, as the 30 end 57' of the escapement lever 54' is forced out by the sloping edge of the advancing tooth 40 of disk 36 against the action of the spring 56'. After the finger 59 has passed over the cam protuberance 60 of the escapement lever 54, the spring 56 returns the escapement lever 54 to its Fig. 5 position, with its end 57 in the path of the advancing tooth 39. It will thus be seen that it is impossible for the receiver to advance a greater 35 distance than one tooth due to its inertia. It will also be understood that when the receiver is in the Fig. 5 position it is locked against rotation in either direction by the escapement levers 54 and 54'.

40 The operation of the receiver for counter-clockwise rotation is the same as that described for clockwise rotation, there being a duplicate set of receiver parts previously described. However, this operation may be 45 again briefly described as follows:

When the transmitter 1 is rotated in a counter-clockwise direction and contact is made between the points 32'-33' the circuit of relay 63' is completed by the following 50 path: battery 65, conductor 68, contact 33', contact 32', conductor 67', winding of relay 63' and conductor 69 to the opposite side of battery 65. The operation of the relay 63' in attracting its armature 64' in turn completes by the following path the circuit of 55 the solenoid 49', the core 50' of which is connected to one end of a rod or the like 52' in turn connected to the arm 51' of the pawl 42' as at 51': battery 62, armature 64' contact 60 of relay 63', conductor 48' winding 79' of

solenoid 49', conductor 61 to the opposite side of battery 62. The winding of the solenoid 49' thus becomes energized and the core 50' is drawn inward, rocking the pawl 42' (which is pivoted to the lever 41' at 43') 70 on its pivot and causing the arm 45' to move from the stop 46' to the stop 47'. Continued movement of the core 50' causes the finger 59' on the arm 44' of the pawl to ride over the cam projection 60' of the escapement 75 lever 54', permitting the latter to be rocked on its pivot 55' by the coil spring 56'. The lever arm 41' is now moved, together with the pawl in a counter-clockwise direction by virtue of the connection between these parts 80 and the rod and spring connection 52'-53' existing between the core 50' and the pawl. The arm 44' is now moved into engagement with a tooth of ratchet wheel 35 advancing the latter one tooth in a counter-clockwise 85 direction thus reproducing corresponding movement of the transmitter, the offset end 57' of the escapement lever preventing spinning of the receiver in an obvious manner.

Upon breaking of the contact between the 90 contact points 32'-33' of the transmitter, current ceases to flow to the solenoid 49' and the spring 53' of the receiver returns the parts to Fig. 5 position. It will thus be seen that no current flows through the circuits 95 while the transmitter is at rest. This cycle of operation is completed as often as contact is made and broken between the points 32'-33' and an impulse sent or interrupted over the wire.

100 It will be noted that where the minimum angular movement which it is desired to transmit is so small as to necessitate a large number of teeth on the disks 3 and 4 and thus make it difficult to give the individual 105 teeth the proper contour the same result may be obtained by gearing up the shaft 5 so that it may be rotated at any relative speed to a driving shaft (not shown).

The receiver may be geared up in like 110 manner, if so desired.

While we have shown but one receiver it will be obvious that any number of receivers remote from one another may be actuated by a single transmitter.

115 From the foregoing it will be seen that we have devised a very simple and efficient apparatus for reproducing rotary motion.

Having thus described our invention, what we claim is:

1. A device of the type described comprising a pair of ratchets revoluble in two directions, a pair of pawls engaged by said ratchets, pivoted contact elements included in an electric circuit controlled by said pawls for 125 imparting electrical impulses, and means engaged by said pawls, compensating for inaccuracies of manufacture or wear of said ratchets.

2. A device of the type described compris- 130

1
ing a pair of ratchets revoluble in two directions, a pair of pawls engaged by said ratchets, contact elements included in an electric circuit controlled by said pawls for 5 imparting electrical impulses, and means co-operative with said pawls adapted to compensate for inaccuracies of manufacture or wear of said pawls or ratchets.

3. A device of the type described comprising a pair of ratchets revoluble in two 10 directions, a pair of pawls engaged by said ratchets, contact elements included in an electric circuit controlled by said pawls for

imparting electrical impulses, and means co-operative with said pawls comprising a centrally pivoted lever engaged by said pawls to compensate for inaccuracies of manufacture or wear of said pawls or ratchets. 15

In testimony whereof we affix our signatures in presence of two witnesses. 20
